UNITED STATES PATENT OFFICE.

SIGMUND L. GOLDMAN, OF CHICAGO, ILLINOIS, ASSIGNOR TO RED SUN PRODUCTS CO.,
OF CHICAGO, ILLINOIS, A CORPORATION OF ILLINOIS.

BOTTLE-CAPPING MACHINE.

Application filed January 27, 1926. Serial No. 84,088.

My invention relates, more particularly, to machines for applying caps, such as metal caps required to be bent into place, to the mouths of bottles to seal them; my primary object being to provide a novel, simple, sturdy and inexpensive type of bottle capping machine which will be highly effective in operation.

Referring to the accompanying drawing:

Figure 1 is a view in side elevation of a bottle-capping machine embodying my improvements. Figure 2 is a section taken at the line 2—2 on Fig. 1 and viewed in the direction of the arrows; and Figure 3, a section taken at the line 3 on Fig. 1 and viewed in the direction of the arrow.

Referring to the particular illustrated embodiment of my invention, the machine comprises a base member 4 shown as adapted to be secured, as by bolts 5, to a table or other support upon which the bottles to be capped rest, it being understood that, if desired, the base member 4 may be provided with a plate extension to overlie the support and serve as the means for directly supporting the bottle to be capped. Rising from the base 4 is an upright 6 formed of a rod which, by preference, extends at its lower end into an upwardly opening socket (not shown) in the base 4 and in which the upright 6 is securely positioned by a screw 7 threaded in the base 4 and engaging the side of the upright, the upright 6 being of circular shape in cross section throughout its length except at the flattened side portion thereof represented at 8.

The upright 6 forms a support for a vertically adjustable capping-head 9 shown as of a form presenting a plate portion 10 carrying rearwardly extending vertically spaced apart lugs 11 containing circular vertically aligned openings therethrough through which the upright 6 extends, this head having sliding fit on the upright. The opposite edge portion of the plate portion 10 is provided with vertically spaced apart lugs 12 and 13 which contain vertically aligned apertures in which a capping-element, represented at 14, is vertically reciprocable. The capping-element is formed of a rod, or stem, portion 15 which slides in the openings in the lugs 12 and 13, and a cup 16 secured to the lower end of the rod 15 below the lug 13 and provided for en-

gagement with the cap to be secured in position on the mouth of a bottle positioned beneath it, this cup being of any suitable form, such as that commonly used in machines of this type, for bending the cap into interlocked position on the mouth of the bottle. The rod 15 is provided with a cross pin 17 located below, and closely adjacent to, the lug 12, and between this stop pin and the bottom wall of an upwardly-opening socket 18 in the lug 13, a coil spring 19 surrounding the rod 15 is interposed. The means shown for depressing the capping-element 14 comprise a lever 20 having a bifurcated portion 21 at which it straddles the head 9 and to which latter it is pivotally secured as by the pivot pin 22, the arms of the bifurcated portion 21 of the lever 20 bearing against the ends of the cross pin 17, whereby when the lever 20 is depressed, it forces the capping-element downwardly against the resistance of the spring 19.

The means employed for holding the head 9 in vertically adjusted position on the upright 6, to adapt the machine for applying caps to bottles of different heights, comprises a friction-plate device formed of a pair of plates 23 and 24 containing apertures 25 through which the upright 6 extends, these apertures being of the same shape as the cross-sectional contour of the upright 8, but of slightly larger size than the cross-sectional area of the upright, whereby these plates are adapted for slight tilting movement relative to the upright. The inner ends of the plates 23 and 24, which are located in the space between the lugs 11, are bifurcated as represented at 125, to provide the spaced lug portions 26 and 27, respectively, at which they straddle the plate portion 9 of the head and underlap and overlie, respectively, bosses 28 and 29 projecting laterally from the head at both sides thereof. A coil spring 30 surrounding the upright 6 and located between the plates 23 and 24 serves to tilt the plate 23 upwardly and the plate 24 downwardly, on their fulcrums 28 and 29 to frictionally grip these plates, and thus the entire head 9, to the upright and thereby hold the head securely against vertical displacement on the upright during the capping operation. The plates 23 and 24, as shown, extend outwardly, beyond the lugs 11 thereby rendering them ac-

cessible to be grasped and pressed together by the operator, against the tension of the spring 30 to release the frictional grip between them and the upright and thereby permit the head 9 to be slid up or down on the upright to any desired position of adjustment, the friction-plate structure just described operating automatically, when the operator releases his grasp on the plates, to 10 securely grip the head to the upright.

In the particular construction shown, and in accordance with the preferred embodiment of my invention, the plates 23 and 24 serve to prevent rotation of the head 9 on the upright, due to the shaping of the openings 25 therein to generally conform with the cross-sectional contour of the upright 6.

It will be understood from the foregoing that a capping machine constructed in accordance with my invention is not only of simple and durable construction, and adapted for ready and positive operation, but also is of relatively inexpensive construction, one of the features thereof rendering the machine of relatively inexpensive construction being that of providing the upright 6 of non-circular shape in cross-section and providing means on the head for preventing the head from turning on the upright preferably by so shaping the openings in the plates 23 and 24 that turning thereof on the upright is prevented. In this connection it will be noted that the necessity of forming the openings through the lugs 11 of non-circular form with attendant expense is avoided.

While I have illustrated and described a particular construction embodying my invention, I do not wish to be understood as 40 intending to limit it thereto, as the same may be variously modified and altered without departing from the spirit of my invention.

What I claim as new, and desire to secure 45 by Letters Patent, is:

1. A capping machine comprising an upright of non-circular cross-section, a capping head slidable along said upright, and friction clutch means on said head and engaging said upright for holding said head in vertically adjusted position comprising friction plates having openings therethrough through which said upright extends, said openings being so shaped as to prevent turning 55 of said plates on said upright.

2. A capping machine comprising an upright of a cross-sectional shape partially circular and presenting a flat side surface, a capping head slidable along said upright, and friction clutch means on said head and engaging said upright for holding said head in vertically adjusted position comprising friction plates having openings therethrough through which said upright extends, said 60 openings being so shaped as to provide por-

tions which cooperate with the flat side surface of said upright to prevent turning of said plates on said upright.

3. A capping machine comprising an upright, a capping head slidable along said upright, and a clutch device on said head for holding the latter in adjusted position on said upright comprising a shoulder on said head, a plate lapping at one end with said shoulder to fulcrum thereon and having a portion which engages said upright and a spring for tilting said plate into clutching position relative to said upright. 75

4. A capping machine comprising an upright, a capping head slidable along said upright, and a clutch device on said head for holding the latter in adjusted position on said upright comprising shoulders on said head, a plate presenting a recess in one end flanked by spaced apart lugs, said lugs lapping said shoulders to fulcrum thereon and having portions which engage said upright and a spring for tilting said plate into clutching position relative to said upright. 80

5. A capping machine comprising an upright, a capping head slidable along said upright, and a clutch device on said head for holding the latter in adjusted position on said upright comprising spaced apart sets of shoulders on said head, plates each presenting a recess in one end flanked by spaced apart lugs, said lugs lapping said sets of shoulders, respectively, to fulcrum thereon and having portions which engage said upright and a spring for tilting said plates 95 in opposite directions into clutching position relative to said upright. 90

6. A capping machine comprising an upright of a cross-sectional shape partially circular and presenting a flat side portion, a capping head having spaced apart bosses containing circular openings therethrough through which said upright extends, said head being provided at its opposite edge with sets of shoulders spaced apart, and means on 105 said head engaging said upright and preventing turning of said head thereon comprising plates containing openings therethrough through which said upright extends, said plates being located in the space between said bosses, the inner ends of said plates containing recesses flanked by spaced apart lugs, said lugs lapping said sets of shoulders, respectively, to fulcrum thereon, and a 110 spring interposed between said plates and yieldingly forcing the latter in opposite directions, the openings in said plates being of a shape corresponding substantially to the cross-sectional shape of said upright 115 thereby forming an interlock between said plates and said upright preventing said plates, and therefore said head, from turning on said upright. 120
